(Continued)*Primary Examiner* — Abraham Bahta(74) *Attorney, Agent, or Firm* — Fleit Intellectual Property Law; Paul D Bianco; Gary S. Winer(57) **CLAIM**

The ornamental design for a floral wrapper, as shown and described.

DESCRIPTION

FIG. 1 is a front view of a floral wrapper according to the present invention;

FIG. 2 is a back view of the floral wrapper of FIG. 1; and, FIG. 3 is a perspective view of the floral wrapper of FIG. 1 in use.

The features shown in broken lines in the drawing depict environmental subject matter only and form no part of the claimed design.
